UNITED STATES PATENT OFFICE

2,610,358

METHOD OF MAKING PIANO ACTION FLANGES

Lloyd M. Martin, San Francisco, Calif., assignor
to Winter & Company, Inc., New York, N. Y., a
corporation of New York

Application December 16, 1949, Serial No. 133,448

4 Claims. (Cl. 18—47.5)

1

This invention relates to the manufacture of what are referred to in the piano art as flanges, by which is meant the brackets which are secured to the action flange rail and which serve as pivot supports for the hammers and other movable components of a piano action. A multiplicity of such flanges is required for each piano and the object of the invention is to facilitate and reduce their cost of manufacture by plastic molding in such fashion that the resulting flanges are complete, even to the inclusion of the necessary bearing material in the journal portions of the flanges.

The invention will be readily understood from the following description taken in conjunction with the accompanying drawings, in which:

Fig. 1 is a broken-out vertical elevation, partially sectioned, of a part of a piano action showing a flange incorporated therein;

Fig. 2 is an enlarged scale sectional view of a flange, the section being taken on the line II—II of Fig. 3;

Figs. 3 and 4 are, respectively, front and rear elevations of the flange of Fig. 2;

Fig. 5 illustrates a preferred form of wrapped core wire suitable in the practice of the method of the invention;

Fig. 6 is a face view of a mold half for molding flanges in accordance with the invention and with the wrapped core wire positioned in the mold; and

Fig. 7 is a view of the complete molded unit as it appears when removed from the mold.

Referring to Fig. 1, a flange 1 is shown attached to action flange rail 2 by screw 3, the flange providing the pivot support for the butt 4 of hammer 5. Such arrangement is of standard, well-known construction.

As shown more particularly in Figs. 2, 3 and 4, the flange consists of a body portion 6, recessed on the back (as at 7) to fit the flange rail, and having a hole 8 to receive the screw 3 by which the flange is secured to the rail. Upstanding from the body portion of the flange are spaced arms 9 which have aligned openings 9a which are lined or bushed with suitable bearing material 10 for the pivot pin 11 of (in this instance) the hammer butt, as shown in Fig. 1.

According to the present invention, such flanges are plastic molded, singly or in groups, with a core sheathed in suitable bearing material so placed in a mold as to form the openings 9a in the flange arms. After removal from the mold, the core is withdrawn, leaving the flange or flanges on or united by the bearing material and

the surplus bearing material protruding from the molded parts is then severed, leaving the pivot holes bushed and ready for use. The bearing material customarily used and suitable for the present method, is felt.

The core referred to preferably consists of a stiff wire 12 (Fig. 5) of the same diameter as the pivot pins with which the flanges are ultimately to be used; and this core is suitably encased in a sheath of bearing material. When felt is used, it is preferably applied in strip form and wrapped helically around the core wire, as indicated at 13 in Fig. 5. The ends of the felt may be temporarily secured to the core wire by clips (not illustrated) or by any other suitable means. At this juncture, if desired, the surface of the felt sheath can be sealed, as by the application of a thin coating of glue.

The core-supported felt or bearing material is then placed in one of the mold halves 14 as illustrated in Fig. 6, the felt being so positioned with respect to cavities 15 as to bridge the cavity portions 16 which, as will be understood, are to form the spaced flange arms 9. The arrangement of the several cavities is schematic only, as will be understood, although for obvious reasons of economy and speed of production it is preferable to mold an extended series of closely spaced flanges at one time. After molding, the complete unit removed from the mold appears as in Fig. 7.

At this stage, the inner or bearing surface of the felt or sheath may be "ironed"; and this may be effected by holding the flanges in a suitable fixture and rotating the core wire. By this means sufficient heat can be generated to effect the ironing. As will be understood, the molding of the flanges directly onto the bearing material effects a bond between the bearing material and the walls of openings 9a in the flange arms, and the core wire can be withdrawn, leaving the series of flanges united simply by the tube of bearing material.

To separate and complete the flanges, it is merely necessary (after removing the core wire) to sever the protruding portions of felt by cutting along the dotted lines shown in Fig. 7, that is to say, along the inner and outer faces of the flange arms 9. As will be recognized, this operation can likewise be performed quickly and economically by means of a series of cutters applied simultaneously to the fixture-held group of flanges. Thus separated and with the openings 55 in their arms 9 lined with the remaining felt

sections, the individual flanges are ready for use.

It will be understood that the plastic materials suitable for making the flanges are the conventional, injection moldable, organic plastics of which a number of varieties are commercially available.

In the light of the foregoing, the following is claimed:

1. The method of making piano action flanges which comprises: wrapping a strip of bearing felt about a core wire so that each turn of said felt is contiguous with each adjacent turn; molding in one molding operation a series of closely spaced plastic flanges about the wrapped core wire and simultaneously therewith attaching said felt to the flanges as the latter are formed; ironing the interior of the felt wrapping by rotating the core wire relatively to the felt; withdrawing the core wire from the felt wrapping and the flanges molded thereon but leaving said felt wrapping attached to said flanges; and severing the felt wrapping protruding from each of the flanges.

2. The method of making piano action flanges which comprises: enclosing a core wire with a sheath of bearing felt; simultaneously molding a series of closely spaced plastic flanges about the felt-enclosed wire and attaching said felt to the flanges as the latter are formed; withdrawing the core wire from the felt and the flanges molded thereon while maintaining the felt attached to the flanges; and severing the felt sheath portions protruding from the flanges.

3. The method of making piano action flanges which comprises: enclosing a core wire with a sheath of bearing material; molding a plastic flange about the sheathed core wire and coincidentally attaching the bearing material to the flange; removing the core wire while maintaining the bearing material attached to the flange; and severing the bearing material protruding from the flange.

4. The method of making bushed plastic piano action flanges which comprises simultaneously molding in one molding operation a group of spaced plastic flanges directly about an elongated core-supported tube of bearing material, bonding the tube of bearing material to the flanges as the latter are formed, removing the core from the tube of bearing material without breaking the bond between said tube and the flanges, and then cutting the bearing material extending from each flange, leaving the bonded bearing material in the flange to serve as bushing.
